(57) **CLAIM**

The ornamental design for an electric hair dryer, as shown and described.

DESCRIPTION

FIG. 1 is a front, top and left-side perspective view of an electric hair dryer showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is back, bottom and right-side perspective view thereof; and,

FIG. 9 is an enlarged view of a portion of the electric hair dryer shown in circled portion 9 in FIG. 7.

The evenly spaced broken lines in the drawings depict portions of the electric hair dryer that form no part of the claimed design. The dot-dash broken lines encircling portions of the electric hair dryer in FIG. 7 and illustrated in the enlarged view in FIG. 9 form no part of the claimed design.
